MULTIPLE TORPEDO

Martin L. Monies, Lafayette, La.

Application March 31, 1942, Serial No. 437,082

1 Claim. (Cl. 114—21)

The invention relates to multiple torpedoes for discharge from naval surface vessels or from aeroplanes, and the primary object of the invention is to provide means whereby a number of torpedoes may be discharged at a target simultaneously and travel toward the target in a coordinated manner, and spread out when approaching the target so as to increase the chances of striking the target and securing multiple torpedo hits thereon.

Other important objects and advantages of the invention will be apparent from a reading of the following description taken in connection with the appended drawing, wherein for purposes of illustration a preferred embodiment of the invention is shown.

In the drawing:

Figure 1 is a general schematic view in top plan showing a multiple torpedo in accordance with the invention traveling toward a target and spreading out upon approaching the target.

Figure 2 is a side elevational view of one of the multiple torpedoes showing the cable drum mounted thereon.

Figure 3 is an enlarged fragmentary transverse vertical sectional view taken through one of the cable drums and its mountings on the torpedo.

Figure 4 is a horizontal sectional view taken through Figure 3 along the line 4—4.

Figure 5 is an enlarged transverse vertical sectional view taken through the center torpedo of a triple torpedo and showing the cable connections thereon.

While the preferred embodiment of the invention resides in the employment of three torpedoes in the manner of a single multiple torpedo, the invention also suggests the employment of two torpedoes in a similar manner or of a greater number of torpedoes than three. In the preferred embodiment of the invention the center torpedo 5, located between the left hand torpedo 6 and the right hand torpedo 7, is provided at a forward portion thereof in a position to clear the torpedo tube 8 with an encircling band 9 which has lugs 10 through which a clamping bolt 11 is extended to clamp the band on the outside of the torpedo. Diametrically opposite points of the band 9 have cable attaching eyes 12 and 13, respectively, which are located in a horizontal plane.

The left hand torpedo 6 and the right hand torpedo 7 have similarly clamped thereon the bands 14 which are similar except that the band on the left hand torpedo carries a cable drum 15 at its right hand side, while the right hand

torpedo 7 carries the cable drum 15' on its band 14 at the left hand side thereof. The cables 16 and 16' connecting the left hand torpedo 6 and the center torpedo 5 and connecting the right hand torpedo 7 and the center torpedo 5 are connected in any suitable manner to the eyes 12 and 13 on the opposite sides of the center or middle torpedo. The outer ends of the cables 16 and 16' are wound on the drums 15 and 15' with the terminals thereof attached to the middle of the drum at approximately the same plane as the eyes 12 and 13 on the middle torpedo, so as to avoid any over-balancing of the torpedoes in transit.

15 The drums 15 and 15' are similar, each comprising upper and lower similar but reversed brackets 17 and 18 which are generally triangular in cross section and are suitably connected by bolts 19 or by other suitable fastening means 20 to the band 14 which encircles the torpedo as shown in Figures 2 and 3 of the drawing. Having its opposite ends journaled in sockets in the outer ends of the brackets 17 and 18 is the axle 20 which is held in place non-rotatably by suitable keys or pins 21. The drum per se which is designated 22 comprises the cylindrical portion 23 and the similar disk-like heads 24 which have angulated faces 25. In the lower head 24 is a flat cylindrical chamber 26 whose peripheral wall 27 is formed with teeth 28, the open bottom of this recess being closed by a plate 29 which fits closely on the axle 20 and is suitably secured to the drum.

35 Pinned as indicated by the numeral 29 to the axle 20 within the recess 26 is the inner end 30 of a spiral flat spring 31 which has its outer terminal 32 conformably shaped to fit between any two of the teeth 27 and be temporarily held in position by this engagement. The spring 31 is 40 coiled in such a direction that as the torpedoes are fired from the torpedo tubes 8 the cables 16 and 16' will be fully wound on the drums 15 with a limited amount of tension on the spiral springs 31. As the torpedoes travel toward the target and some tension is naturally exerted from the cables due to slight deflections in the courses of the torpedoes, the springs 31 will be tensioned, so as to cause the terminal 32 to more firmly engage the teeth 27 until a point is reached in the 45 winding of the springs whereat the tension of the springs is such as to cause the terminal 32 to jump along the teeth 27 and thereby permit a corresponding amount of the cables 16 and 16' to pay out and allow the torpedoes to separate 50 in opposite directions with respect to the middle

torpedo 5. The spring arrangements in the drum and the teeth 27 are so proportioned and arranged that by the time the triple torpedo is approaching its target, the cables 16 and 16' will have been paid out to approximately the full length thereof, so that the torpedoes will be following diverging spread courses, as indicated diagrammatically in Figure 1 of the drawing. It is obvious that the torpedoes, in the event of an approach such as is illustrated in Figure 1 of the drawing will achieve multiple spaced hits on the target vessel 32 at much more widely spaced points than the points of discharge from the torpedo tubes 8 on the attacking vessel or plane 33. It will also be obvious that in the event that the triple torpedo disclosed herein strikes the target vessel near either end thereof, the target vessel will engage one of the cables 16 and 16', so as to cause the triple torpedo to "wrap" around the end of the vessel, and all of the torpedoes may take effect on the target vessel simultaneously or successively.

Although there is shown and described herein a preferred embodiment of the invention it is to be definitely understood that it is not desired to limit the application of the invention thereto,

except as may be required by the scope of the subjoined claim.

Having described the invention, what is claimed as new is:

5. A triple torpedo assembly adapted for discharge simultaneously from triple torpedo tubes and comprising a middle torpedo, and right and left hand torpedoes, respectively, and means to yieldingly couple said pair of torpedoes to opposite sides of the middle torpedo, respectively, for travel of said pair in divergent paths relative to the path of travel of the middle torpedo, said means comprising a pair of drums rotatably mounted on said pair of torpedoes, respectively, 10 flexible elements wound on said drums and connected to said opposite sides of the middle torpedo and adapted to be unwound under pull exerted thereon from said drums, and devices in said drums for yieldingly opposing rotation thereof in directions to unwind said elements and in variable degree under pull in varied degree on said flexible elements, said devices comprising ratchet teeth, and helical springs provided with tooth dogging ends.
